Inventor

Samuel Shreffler Jr.

UNITED STATES PATENT OFFICE.

SAMUEL SHREFFLER, JR., OF MORRIS, ILLINOIS.

DOOR-HANGER.

SPECIFICATION forming part of Letters Patent No. 281,686, dated August 31, 1880.

Application filed January 30, 1880.

To all whom it may concern:

Be it known that I, SAMUEL SHREFFLER, Jr., of the city of Morris, in Grundy county and State of Illinois, have invented certain 5 Improvements in Door-Hangers, the construction and operation of which I will proceed to explain, reference being had to the annexed drawings, and the letters and figures thereon, making a part of this specification, in which—
10 Figure 1 is a side elevation; Fig. 2, a front elevation of a roller; Fig. 3, a side elevation of a single hanger; Fig. 4, a cross-sectional view of the track; Fig. 5, a plan view of the details of the track, and Fig. 6 a side view of the details of the track.

This invention relates to the construction of the rollers upon which the door hangs and rolls from side to side, which rollers may be applied to bar-doors or doors of a dwelling, 20 especially sliding doors; and the improvement I claim to have made relates to the contrivance for preventing the rollers from getting out of place and changing their distance from each other without their being connected with 25 each other by a reach or otherwise.

In the drawings, B is the side of a building, and D is a door of the kind that slide from side to side to close the opening.

b is a rail that is fastened to the side of the 30 building, over the opening just next to and immediately over the door D, and in length twice the width of the door. On the top of the rail b the track is laid, which track consists of a metal strip, x, or strips jointed together, as 35 shown in Fig. 5, on the top of which metal strip, and along its central line, is a wooden strip, n, (shown particularly in Fig. 4 in cross-section,) which strip n is fastened to the metal strip by bolts or nails, to be firm, and serves 40 as a guide for the grooved rollers a to travel over, as is shown in Fig. 2 in cross-section, the metal strip x forming the track upon which the rollers a roll and rest, as shown in Figs. 1, 2, and 3. The door hangs from the cross-bar i 45 by the arms P P, and the cross-bar i rests upon

the racks c c, one at either end, which racks rest on the central cogged axles, r, of the grooved rollers a, as shown in Figs. 1, 2, and 3, between the two flanges of the rollers a. These grooved rollers are entirely separate 50 and disconnected from each other, and are held in place and at the proper distance from each other by means of the cogged axles r meshing into the cogs of the racks c, as shown in Fig. 1.

When the door is long the construction of the frame i P may be as is shown in Fig. 3, one at each corner of the door, for greater strength and security.

By constructing the rollers a in this form, 60 and by the use of the rack c, no jar or jam of the door can slide the rollers along so the door can run off the rollers, and the door runs so easily a child can move it.

Fig. 6 shows the mode of fastening the track 65 x and rails n and b together by nails or bolts. The metal strip x is first nailed to the wood guide-strip n at the lower side, and then the track thus formed of a strip of wood and metal is nailed or bolted down to the rail b, as shown 70 in said Fig. 6, which forms a rail or track combined of wood and metal that is very cheap and not liable to break, as when they are made of cast-iron.

Having thus described my invention, what 75 I claim as new, and desire to secure by Letters Patent, is as follows, to wit:

1. The combination and arrangement of the grooved rollers a, central cogged axle, r, and toothed racks c, for the purpose of supporting 80 and sliding the door D, in the manner set forth.

2. The track to support and guide the grooved rollers a, consisting of the flat metal strip x and wood rail n, attached thereto, arranged to operate as and in the manner described.

SAMUEL SHREFFLER, JR.
